FIG. 5

FIG. 6

FIG. 1 is a side elevational view of our new design for a tractor cab, and showing, in dot-dash lines, a tractor on which said tractor cab is mounted. The side opposite is the same as the side shown.

FIG. 2 is a front elevational view of FIG. 1.

FIG. 3 is a rear elevational view of FIG. 1.

FIG. 4 is a top plan view of FIG. 1, but showing only said tractor cab.

FIG. 5 is a rear perspective view of our new design shown in FIG. 1.

FIG. 6 is a side perspective view of a fragment of the front of the cab, with the view being taken from the side shown in FIG. 1.

The dot-dash lines are for illustrative purposes only.

We claim:

The ornamental design for a tractor cab, substantially as shown and described.
